UNITED STATES PATENT OFFICE.

WILLIS C. MERRILL, OF BOSTON, MASSACHUSETTS, ASSIGNOR, BY MESNE ASSIGNMENTS, TO THE MERRILL PROCESS COMPANY, OF BOSTON, MASSACHUSETTS, A CORPORATION OF MASSACHUSETTS.

HEATING APPARATUS.

1,325,952.

Specification of Letters Patent. Patented Dec. 23, 1919.

Application filed February 14, 1916. Serial No. 78,271.

To all whom it may concern:

Be it known that I, WILLIS C. MERRILL, of Boston, in the county of Suffolk and State of Massachusetts, have invented certain new and useful Improvements in Heating Apparatus, of which the following is a specification.

My invention relates to new and useful improvements in heating apparatus and especially adapted to control or regulate the flow of fuel to heaters employing gas, fuel oil or other burners, and in which apparatus a circulating heating fluid or liquid medium is employed for heating materials or substance by the radiation thereby of the heat units of said circulating heating fluid or liquid medium inclosed, heated and circulated in a suitable conduit.

The main object of my invention is to provide an apparatus adapted upon the retarding or stoppage of the circulation of the circulating heating fluid or liquid medium, owing to trouble with the motor and pump or for any other reason, to automatically cut off the fuel supply, and thereby prevent any increase in temperature of the circulating heating fluid or liquid medium which will gradually fall in temperature owing to the cutting off of the fuel supply to the burner of the heater.

This and other objects are accomplished by the apparatus hereinafter described and illustrated in the drawings.

In the accompanying drawings which illustrate a construction embodying my invention:

Figure 1 is a side elevation of a heating apparatus employing my invention to cut off the supply of fuel upon the retarding or stopping of the pump and motor thereby preventing any increase in temperature in the heater thereby avoiding damage or injury to the circulating heating fluid or liquid medium or to the apparatus.

Fig. 2 is a side elevation partly in section of the valve mechanism for controlling the valve in the fuel oil supply pipe and showing the valve open to allow a flow of fuel to the burner.

Fig. 3 is a similar view to Fig. 2 and showing the controlling valve in the fuel oil supply pipe closed to cut off the flow of fuel to the burner.

Fig. 4 is a side elevation of the valve

mechanism and valve for controlling the flow of fuel to the burner open.

Fig. 5 is a side elevation of the valve mechanism and valve for controlling the flow of fuel to the burner closed.

Fig. 6 is a modification of the controlling valve in the fuel oil supply pipe and the mechanism for operating the same with the controlling valve shown open to allow a flow of fuel to the burner.

Fig. 7 is a similar view to Fig. 6 of the modification and showing the controlling valve in the fuel supply pipe closed to cut off the flow of fuel from the burner.

Like letters of reference refer to like parts throughout the several views.

I have illustrated my invention as applied to a heating apparatus in which a circulating heating fluid or liquid medium, as a mineral oil, is employed as the heating agent, and this oil which is supplied to an expansion or supply tank 32 feeds down the pipe 69 past the hand valve 31 to the pipe 42 thence into the force pump A, through the pipe 30, through the coil B located in the heater 28 and then out through the pipe 29, to the hollow bearing 74 to the calender roll 49 and out through the hollow bearing 75 supported on the posts 72 and base 50, and then the said circulating heating fluid or liquid medium passes through the pipe 42 back to the pump A thus forming a complete inclosed heating conduit. In this conduit is circulated under pressure by the pump A a heating fluid or liquid medium, preferably a mineral oil, having a boiling point above 212° F. and a high carbonizing point, so that the temperature of this mineral oil may be raised in the heater B to high temperatures without carbonization, say 500° F. or higher, owing to the rapid circulation thereof by the pump A, which forced circulation causes new surfaces of the heating fluid or liquid medium to be continuously presented to the heater 28, and in the continued circulation of said heating fluid or liquid medium the heat units thereof are uniformly distributed to the material or substances under treatment. This forced circulation with the rapid absorption and transmission of the heat units prevents the carbonization of the circulating heating fluid or liquid medium and consequent injury to the circulating fluid or damage to

the apparatus. The pump A is driven by an electric motor 41 receiving its power through the wires 38 and 39, in which circuit is interposed a rheostat 43 in turn connected 5 with the panel 44 by the wires 47 and 48 and controlled by a hand switch 69 controlling the main circuit through the wires 45 and 46. The motor 41 and pump A are supported on a suitable base 40.

- 10 The burner 11 receives its fuel supply from the tank 1 through the pipes 18 and 16 controlled by the hand valves 17 and 12 and in said pipe 16 is a valve controller 14 in which is located the magnets D which, when 15 the apparatus is in operation, is energized by the branch electric circuit through the wires 26 and 27 secured by the contact screw 66 to the valve controller 14.

This closed circuit through the wires 26 20 and 27 energizes the magnets D and lifts the armature E with the valve rod H and its valve 60 to an upper position, as shown in Fig. 2, to allow a clear flow of fuel through the pipe 16 and port M in the 25 valve casing 13. The movements of the armature E and valve rod H are guided by a yoke consisting of the vertical rods F which pass through guides G on opposite sides of the valve casing 13 and carry on 30 their lower end a weight 5 provided with lugs P through which rods F pass and said weight 5 is secured in place by the lock nuts K.

Now if the circuit to the motor 41 should 35 fail and the motor and pump stop, or their normal operation be interfered with for any reason, then the branch circuit through the wires 26 and 27 would be broken and the magnets D become deenergized allowing the 40 armature E and weight 5 to drop from the position shown in Fig. 2 to that shown in Fig. 3, thereby closing the valve 60 and cutting off the fuel supply through the pipe 16 to the burner 11.

45 As the valve 60 and weight 5 drop the contact fingers L and N engage one another and close the circuit through the wire 20, held in place by the contact screw 67, and the battery 21, thereby starting the bell 23 50 to give an alarm to the attendant who may stop the alarm by operating the hand switch 74. A source of air is supplied through the pipe 8 to the burner 11 through the T-joint 10 in the pipe 16 and is controlled by a hand valve 9 and a valve controller 6 of similar construction to the valve controller 14 (Figs. 1, 2 and 3) for the fuel supply pipe 16, and operates in identically the same manner as said valve controller 14, so 55 that when the motor and pump are running and the apparatus is in operation the valves in the valve controllers 14 and 6 are held open by the branch electric circuits from the main circuit and the supply of air and fuel flows 60 freely to the burner 11, and upon the break-

ing of the circuits, as above described, the fuel oil supply in the supply pipe 16 and the air supply in the pipe 8 are both automatically cut off until the electric circuit is again closed and repairs made, if any are 70 necessary. By thus automatically cutting off the fuel supply to the pipe 16 of the burner 11 the temperature at the burner 11 lowers so that the heating fluid or liquid medium which has stopped circulating or is 75 sluggish owing to the retarding or stoppage of the pump and is not raised in temperature to a dangerous point, but decreases by the lack of the supply of fuel to the burner 11 and the cooling off of the heater by radiation to the atmosphere, so that no carbonization of this circulating heating fluid or liquid medium with the consequent damage due to crystallization of the conduit takes 80 place, and as the apparatus is thus automatically stopped and the temperature lowered any further liability of damage or injury to the apparatus is avoided.

When the circuit is reestablished and the 85 motor and pump are in operation, the circuits to the valve controllers 6 and 14 are closed, and the controlling valves therein are automatically opened to allow a free flow of the fuel and air to the burner 11 for the heating of the oil again started in 90 circulation by the pump A upon the closing of these branch circuits 26, 27, 24 and 25.

From all of the foregoing it will be understood that upon the motor and pump starting in the operation of the apparatus, 100 both the valves controlling the air and fuel supply are automatically opened, and that upon the stoppage of the motor and pump both the valves in the air supply and fuel supply pipes are automatically closed. 105 While I have shown two valve controllers, one in the fuel supply and the other in the air supply, it will be understood that only one could be used, preferably the one to cut off the fuel supply upon the stoppage of the 110 pump, yet it is advantageous to provide another controller in the air supply pipe so that in case the valve in the fuel supply pipe should stick or for any other reason not work, the one in the air supply pipe would 115 work and cut off the necessary air for the combustion at the burner, and also cut off the air pressure to the tank 1 for forcing the fuel supply to the burner 11 through the pipes 18 and 16.

120 In Figs. 6 and 7 I have shown the modification of the valve controlling the fuel supply and mechanism for operating the same, and this modification differs from the valve controller 14 in that the valve in the 125 fuel or air supply pipes is opened by a manual operation upon the restarting of the pump and the motor and the purpose is to provide an extra safeguard so that the valves controlling the fuel and air supply 130

pipes may not accidentally be opened until the pump and motor are in proper working order. In this construction, when the circuit is again made and the motor and pump are operating the magnets 51 are energized by the branch electric circuit through the wires 26 and 27 secured by the contact screw 66 to the valve controller 76, and this closed circuit holds the armature 64 with the roll 56 on the upper end of the said armature 64 supporting the weight 58 as shown and holding the valve 60 in an open position with the passage 61 in the valve casing 13 open (Fig. 6) and affording a clear flow 15 of the fuel through the pipe 16. A spring 53 secured on one end to the side of the valve controller 76 by the pin 65 and at its other end to the upper end of the armature 64 tends to pull the armature 64 away from 20 the magnets 51 (Figs. 6 and 7) into contact with a stop pin 57 to limit its movement. Now if the circuit to the motor should fail and the motor or pump stop, the branch circuit 26 and 27 would be broken and the magnets 25 51 deenergized permitting the spring 53 to pull the armature 64 from the position shown in Fig. 6 to that shown in Fig. 7, thereby allowing the weight 58 to drop and with it the valve 60 closing the fuel 30 supply pipe 16 (Fig. 7). As the weight 58 drops the contact fingers 62 and 63 secured respectively to the wires 19 and 20 by the contact pieces 68 and 67 engage one another and close the circuit through the wires 19 35 and 20, the battery 21 and wire 22 and bell 23, thereby starting the bell 23 to give an alarm to the attendant, who may stop the alarm by operating the hand switch 74. After the motor and pump are again in operation 40 the valve 60 in the fuel supply pipe 16 may be raised by operating the handle 15, when the parts move from the positions shown in Fig. 7 to the positions shown in Fig. 6, so as to provide for a flow of air 45 and fuel to the burner 11 and break the secondary circuit to the alarm bell 23, thus putting the apparatus in condition to be operated as hereinbefore described upon the next stoppage of the pump or motor. 50

If for instance by reason of some extraneous matter, like a piece of scale from the pipe, or for other cause obstructing the operation of the motor or pump, the circulating heating fluid or liquid medium should be 55 caused to stop circulating or to run sluggishly and an overload thereby be imposed upon the motor, or for any other reason the motor should be arrested or stopped, damage may be avoided by providing a fuse 52 in 60 the main line 46 which will be adapted to blow out when the current reaches a predetermined strength and thereby break the circuit to the motor and also the circuits to the valve controllers 14 and 6 and start the 65 bell 23 to give the alarm, so that when the

motor or pump, or both, stop either from the failure of the main circuit or from causes as above stated then the fuel supply to the burner is automatically cut off during the stoppage of the pump and motor, and upon the restarting of the apparatus the controlling valves in the air and fuel supply pipes for the burner are either automatically opened by the closing of the main circuit, or opened manually as described for the construction illustrated in the modification, Figs. 6 and 7. 70

In this apparatus it is intended to have no built up pressure, so that the circulating oil is free to expand and by placing the feed 80 pipe from the expansion tank 32 on the suction side of the pump A, expansion of the circulating oil is provided for without interfering with the circulation of the same, and any lack of circulating oil is supplied 85 by the tank 32 to complete the circulation. Otherwise if the feed pipe from the expansion tank 32 were connected on the pressure side of the pump A, any pressure that might occur would tend to drive the circulating oil 90 up into the expansion tank 32 rather than through the conduit containing the circulating heating fluid or liquid medium.

The pipe 37 on the pressure side of the pump communicates to the top of the expansion tank 32 and affords relief of any excess pressure arising at any time in the continuous conduit in which the circulating heating liquid is circulated by operating the hand valve 34 or automatic relief may be 95 provided through the pipes 36 and 70 and automatic relief valve 35 of any such excess pressure due to any cause interfering with the normal circulation of the circulating heating liquid. 100

While I have shown and described my invention as applied to heating apparatus in which a heating fluid or liquid medium, as a mineral oil, is circulated as a heating medium for treating materials by the radiation 110 of its heat units, yet it will be understood that my invention might be applied to other forms of apparatus using a heating fluid or fuel supply other than a mineral oil. And further while I have shown my invention as applied to an apparatus for heating calender rolls, yet it will be understood that it may be equally well adapted to other heating devices for other uses and purposes, such as heating metal surfaces, pressure rolls and cylinders, burnishers, cloth driers, vulcanizers, heating and liquefying asphalt, bituminous or other materials requiring heat for their liquefaction, also in the arts of distilling, brewing, dyeing, soap making, sugar 120 making, and for any other uses and purposes where heat is required and especially heat at high temperatures.

While I have illustrated and described my invention as applied to a machine where 130

electric power is used, yet it will be understood that it may be used with apparatus employing any other source of power in which cases suitable mechanical devices 5 would be provided which upon the stoppage of the pump or motor, or both from any cause would operate to automatically cut off the supply of fuel to the burner or both the supply of fuel and air to the burner if desired to cause a falling off of the temperature in the heater and thereby prevent damage and injury to the apparatus, and upon the restarting of the apparatus these valves would be either automatically or manually 15 opened as desired.

Having thus described the nature of my invention and set forth a construction embodying the same, what I claim as new and desire to secure by Letters Patent of the 20 United States, is:

1. In a heating apparatus, a source of heating fluid medium, a conduit through which said heating fluid medium is circulated, a heater for heating said heating fluid 25 medium as it circulates through said conduit, a source of fuel supply for said heater, means for circulating under pressure the said heating fluid medium to absorb the heat units of the heater and uniformly distribute 30 the same to the material under treatment, a motor for operating said circulating means, a valve controlling the supply of fuel to said heater, a valve controller for said valve, an electric circuit for operating said motor and 35 for controlling said valve controller to open said valve and allow a flow of fuel to the heater during the operation of the motor and upon the motor becoming inert to allow said fuel supply controlling valve to close

automatically and cut off the fuel supply to 40 the heater and upon the restarting of the motor to operate said valve controller to open automatically said fuel supply controlling valve to permit a supply of fuel to the heater, and an alarm adapted to be automatically set off upon the stoppage of the 45 motor.

2. In a heating apparatus, a source of heating mineral oil, a conduit through which said heating mineral oil is circulated, 50 a heater for heating said heating mineral oil as it circulates through said conduit, a source of fuel supply for said heater, means for circulating under pressure the said heating mineral oil to absorb the heat units of 55 the heater and uniformly distribute the same to the material under treatment, a motor for operating said circulating means, a valve controlling the supply of fuel to said heater, a valve controller for said valve, an 60 electric circuit for operating said motor and for controlling said valve controller to open said valve and allow a flow of fuel to the heater during the operation of the motor and upon the motor becoming inert to allow said fuel supply controlling valve to close automatically 65 and cut off the fuel supply to the heater and upon the restarting of the motor to operate said valve controller to open automatically said fuel supply controlling 70 valve to permit a supply of fuel to the heater, and an alarm adapted to be automatically set off upon the stoppage of the motor.

In testimony whereof I have signed my 75 name to this specification.

WILLIS C. MERRILL.
